UNITED STATES PATENT OFFICE.

LOUIS C. VANDERLIP, OF ELKHART, INDIANA.

HOOD CLAMP FOR AUTOMOBILES.

Application filed December 11, 1926. Serial No. 154,055.

This invention relates to automobile devices, and especially to hood clamps therefor.

The principal object of the invention is to provide a clamp which exerts both a downward and a lateral pressure upon the hood, the lateral pressure being effected by cam means.

Another object of the invention is to provide a clamp for an automobile hood wherein the hold-down clamp is connected with a keeper the lower end whereof exerts a lateral pressure on the hood by cam action.

Other and more specific objects of the invention are mentioned and described herein.

The preferred embodiment of the invention is illustrated in the accompanying drawing, wherein Figure 1 is a side elevation of a hood clamp and an automobile hood illustrating the application of the invention thereto; Fig. 2 is a front elevation thereof in fragment taken on line 2-2 of Fig. 1; Fig. 3 is a section taken on line 3-3 of Fig. 1; and Fig. 4 is a side elevation illustrating a fragmental modification of the invention.

Referring to the details of the drawing the numeral 1 represents a frame section of a motor car to which the hood abutment element 2 is rigidly attached interiorly of the hood to limit the inward movement of the engine hood 3 when the latter is subject to pressure exerted by a hood clamp, as herein-after described.

The numeral 4 represents a clamp keeper which may be rigidly secured to the hood 3 by rivets 5, 5 and adapted to receive the hook of a spring hold-down clamp herein-after described.

The hold-down portion of the clamp may comprise the hollow cylindrical spring casting or barrel 6 which is apertured and constricted at its lower end to admit the passage of the usual spring rod 7 and within

which the usual coil spring 8 is arranged in encompassment of the rod 7, said spring being seated on the rod head 9 and the lower constricted end wall of the casing 6. The upper end of the spring casing 6 may be rigidly socketed in a latch element 10 which

may be provided with a handle 11 and a hook 12 disposed on opposite sides thereof, said hook being adapted to resiliently engage the keeper 4 to effect the downward pressure on the latter and thereby the hood. The upper edge of the keeper 4 may be con-

caved or recessed in any suitable manner at 21, the point of engagement by clamp hook 12, to prevent lateral displacement of said hook.

The lower end of the slidable spring rod 7 may be provided with a hinge eye 13 for pivotally connecting same, and the clamp unit, with the hinge pin 14 mounted in the forked bracket 15 carried by the base element 1. The numeral 16 represents a cam bracket angularly disposed relatively to the hood 3 and which may be rigidly mounted upon the base element 1 intermediate the bracket 15 and the hood, for which purpose said cam may be provided with the base section 17 upon which the bracket 15 may be arranged, fastener bolts 18 passing through both of said elements to secure them to the frame section 1. Preferably, the cam element 16 is inclined outwardly from the upright hood 3 and may be made of spring steel, the lower end of the cam being arranged nearer the hood than the upper end thereof, but the lower end of said cam is disposed laterally of and outside of the path of downward movement of the lower edge of the hood 3 to permit unrestricted downward action thereof. The lower end or edge of the hood may be spaced from and above the frame section 1 to permit unrestricted downward and slidable movement of the hood on the stop element 2 under pressure of the clamp and cam means, as hereinafter described.

The cam 16 is adapted to coact with the cam element 19 carried by the hood 3 and which may be a downward extension of the body of the keeper 4 and outwardly bent and spaced from the hood. Preferably, the cam element 19 is bent to conform to the contour of the stationary cam 16 to facilitate the guiding of the hood into position when the latter is lowered.

In the modification illustrated in Figure 4 the body of the keeper 4 is extended straight down to a point adjacent the lower edge of the hood and then upwardly and outwardly bent at 20 to conform with the angle of the fixed cam 16.

In a device of this character it is very essential that the means used to prevent rattle of the hood shall exert both a downward pull as well as a lateral thrust on the hood, and the latter must be very substantial to prevent rattle of the hood on the stop element 2, and the lateral thrust on the hood

must be sustained as well as substantial. To effect the sustained lateral pressure on the hood to project and hold the latter against the stop element 2 the cam mechanism described is provided, whereby, when clamp hook 12 engages the keeper 4, the downward pull thereof, exerted by spring 8, causes the cam 19 to engage the stationary cam 16 with an increasing and direct pressure, thereby 10 effecting a positive and sustained lateral pressure upon the hood.

I have illustrated the preferred and a modified form of the invention, but it will be evident that changes may be made therein, 15 within the spirit and scope thereof, as defined in the appended claims.

I claim:—

1. In an automobile hood-clamp, the combination with a hood of a combined keeper 20 and cam element rigidly secured to the hood exterior, a spring-actuated hold-down clamp positioned exteriorly of the hood and connected with said keeper, and a stationary cam element arranged exteriorly of the hood 25 and adapted to coact with the cam section of said keeper for laterally projecting the hood.

2. In an automobile hood-clamp, the combination of a spring-actuated hold-down clamp positioned exteriorly of the hood, a 30 hood abutment, and resilient cam means engaged by the hood when depressed by said hold-down clamp for projecting the hood laterally against said abutment.

3. In an automobile hood-clamp, the combination of a hood, a base frame element, a 35 spring actuated hold-down clamp arranged exteriorly of the hood, and a resilient cam connection between said hood and base frame element adapted to direct pressure inwardly 40 against said hood.

4. In an automobile hood-clamp, the combination of a hood, a base frame element, a spring actuated hold-down clamp arranged exteriorly of the hood, and a resilient stationary cam element arranged exteriorly of 45 said hood and carried by said base frame element, said cam being adapted to be engaged by the hood when the latter is depressed by said hold-down clamp for projecting the hood inwardly and laterally.

5. In an automobile hood-clamp, the combination with a hood, of a combined keeper and cam element secured to the hood, said cam element being positioned below said 55 keeper, a spring actuated hold-down clamp positioned exteriorly of the hood and connected with said keeper, and an abutment element adapted to coact with said cam element for laterally projecting the hood.

6. In an automobile hood-clamp, the combination with a hood, of a combined one piece keeper and cam element secured to the hood exterior, said cam element being positioned adjacent the lower end of said keeper 60 and cam element, a spring actuated hold-

down clamp positioned exteriorly of the hood, and a stationary cam element arranged exteriorly of the hood and adapted to coact with said cam carried by the hood for laterally projecting the hood upon engagement of 70 said keeper by said hold-down clamp.

7. In an automobile hood clamp, the combination of a hood, a base frame element, a hood abutment within the hood, a spring actuated hold-down clamp mounted exteriorly of the hood and adapted to exert downward pressure upon the hood, and coacting cam means directly connecting said hood and base frame element, for laterally and inwardly actuating the hood against 75 said hood abutment, said cam means being arranged wholly outside of the hood and laterally of the downward path of movement of the lower edge of the hood to permit of unrestricted downward and inward movement of said hood.

8. In an automobile hood clamp, the combination of a hood, a base frame element, a hood abutment within the hood, a spring actuated hold-down clamp mounted exteriorly of the hood and adapted to exert downward pressure upon the hood, and coacting cam means for laterally and inwardly actuating the hood, said cam means comprising a cam carried on the hood exterior, 90 and a cam carried by the base frame element laterally and outside of the downward path of movement of the hood lower edge.

9. In an automobile hood clamp, the combination of a hood, a hood abutment within the hood, a spring actuated hold-down clamp positioned exteriorly of the hood and adapted to exert downward pressure upon the hood, a cam carried upon the hood exterior, a stationary cam mounted exteriorly of the hood and in the path of movement of said hood cam, whereby downward pressure of the hold-down clamp actuates the hood inwardly, causing the inside surface only of 100 said hood to engage said abutment.

10. In an automobile hood clamp, the combination of a hood, an abutment within the hood, a spring actuated hold-down clamp positioned exteriorly of the hood and adapted to exert downward pressure upon the hood, and coacting cam elements arranged exteriorly of the hood, one of which cam elements is mounted upon the side of the hood and is a separate element, for projecting the hood laterally and inwardly 115 against said abutment with sustained pressure.

11. In an automobile hood clamp, the combination of a base frame element, a hood, a hood abutment within the hood, a spring actuated hold-down clamp positioned exteriorly of the hood and adapted to exert downward pressure upon said hood, stationary cam means carried by said base frame element, and a cam mounted upon the hood 125 130

- exterior and above the lower edge thereof, whereby downward actuation of the hood by said hold-down clamp actuates the hood inwardly against said abutment with sustained pressure thereon.
12. In an automobile hood clamp, the combination of a hood, an abutment within the hood, a spring actuated hold-down clamp positioned exteriorly of the hood and adapted to exert downward pressure upon the hood, and coacting cam elements arranged exteriorly of the hood, one of which is mounted upon the hood side, for projecting the hood laterally and inwardly against said abutment, said cam elements being provided with coacting inclined substantially straight faces.
13. In an automobile hood clamp, the combination of a hood, a base frame element, a spring actuated hold-down clamp arranged exteriorly of the hood and adapted to exert downward pressure upon the hood, said clamp being carried by said frame element, a hood abutment within the hood, and coacting cam means for laterally and inwardly actuating the hood against said hood abutment as the hood is downwardly actuated by the hold-down clamp, said cam means including a stationary cam mounted adjacent the base of the hood and separate and spaced from said hood abutment.
14. In an automobile hood clamp, the combination of a hood, a base frame element, a hood abutment within the hood, a spring actuated hold-down clamp mounted exteriorly of the hood and adapted to exert downward pressure upon the hood, and coacting cam elements positioned wholly exteriorly of the hood for laterally and inwardly actuating the hood against said hood abutment, one of said cam elements being carried upon the exterior of the hood, the lower edge of said hood terminating short of said base frame element to provide a clearance to permit unrestricted downward movement of the hood when actuated by said clamp.
- In witness whereof I have hereunto affixed my signature this 8th day of December, 1926.
- LOUIS C. VANDERLIP.
